UNITED STATES PATENT OFFICE.

ELROY N. HEATH, OF WAKEFIELD, MASSACHUSETTS, ASSIGNOR OF ONE-HALF TO JAMES FRED PARKER, OF WAKEFIELD, MASSACHUSETTS.

CARD-HOLDING DEVICE.

SPECIFICATION forming part of Letters Patent No. 753,882, dated March 8, 1904.

Application filed February 28, 1903. Serial No. 145,510. (No model.)

To all whom it may concern:

Be it known that I, ELROY N. HEATH, a citizen of the United States, residing at Wakefield, in the county of Middlesex and State of Massachusetts, have invented an Improvement 5 in Card-Holding Devices, of which the following description, in connection with the accompanying drawings, is a specification, like letters on the drawings representing like parts.

10 My invention consists in a new and improved form of card-holding device and may be employed in connection with a variety of games and for many different purposes.

15 My invention will be best understood by reference to the following description and accompanying illustration of one specific embodiment thereof particularly intended to carry out the game of duplicate whist, in connection with which I have found my invention 20 to have particular utility.

Referring to the drawings, Figure 1 is a plan view of one form of my card-holding device looking from the top with the card-pockets spread open. Fig. 2 is a similar plan view looking from the bottom. Fig. 3 is a view showing the card-pockets partially closed. Fig. 4 is a view in perspective showing the card-pockets in their closed position with the separated parts of the card-pack secured therein. Fig. 25 30 5 shows a modified form of fastening device. Fig. 6 illustrates the manner in which the said card-holding device may be employed as a card-case to hold unseparated an entire pack of cards, and Fig. 7 is an end view of the same.

35 Referring to the drawings, when I employ my invention in connection with duplicate whist I preferably employ four card-holders, which herein I show in the form of pockets *a*, *b*, *c*, and *d*, although for other purposes 40 the number of these holders may of course be varied. These pockets may be made of any suitable material and in any suitable form; but I prefer to construct the same as shown in the drawings, where the card insertion or 45 open ends of the pockets assume outwardly radiating positions when the pockets are extended or spread open, as shown in Figs. 1 and 2. The pockets preferably near or toward their opposite ends are secured in some man-

ner, as by the pivotal or hinged connection 50 afforded by the tape or string *e*, which is preferably fixedly secured to the outer sides of the outer pockets and passes freely through holes in the inner pockets and the inner sides of the outer pockets, which may be eyeleted, 55 if desired. This forms a simple and effective pivotal connection and also provides for a use, to which I will refer, for the separate pockets; but it is of course to be understood that in this as well as other details my invention 60 is in no wise limited to the construction shown. It will be seen that the holders are serially connected—that is, the connecting means engages the several holders in series. The ends of the pockets opposite the card insertion or 65 open ends may be closed, if desired, or for the sake of simplicity they may be constructed as shown in Fig. 4, where the cord or tape *e* prevents the escape of the cards from those ends of the pockets. The pivotal connection de- 70 scribed permits the same to be spread open in a fan-like manner, as shown in Figs. 1 and 2, or to be brought together to register one with another, as shown in Fig. 4, or to assume any intermediate position, as illustrated 75 in Fig. 3.

By constructing the card-holding device so that the holders move parallel to the faces of the contained cards and so that the faces of the cards themselves are arranged in parallel 80 relation in both collapsed and extended positions the device may be laid flat upon the table before the players in either collapsed or extended position, and when in the latter position, lying flat on the table, is in a situation 85 to receive the cards or permit their withdrawal, as becomes necessary during the play, with the utmost facility.

In playing duplicate whist it is desirable that each of the hands of cards, which in the 90 device herein described may be placed in the several pockets, should be placed in front of the player and that the pockets when spread open should therefore assume positions substantially ninety degrees apart. For the purpose of thus spacing the pockets when the same are opened I employ a spacer consisting of the cord or tape *f* or other suitable means 95

shown herein, secured to the back of each pocket, so that when the case is spread open, as shown in Fig. 2, the spacer compels the pockets to assume their proper positions.

5 When the pockets are closed over each other, the cord slides in between the several pockets, as shown in Fig. 3.

The pocket *a* is provided with a flap *g*, having an eyelet-hole *h*, such that when the pockets are in the closed-in position the flap may be brought over and to inclose the open ends of the pockets, in which position it may be held by placing the eyelet-hole *h* over the button *i* upon the outer face of the pocket *b*.
15 The flap is secured in this position by the snap *k*, adapted to snap over the button *i* and carried by the free flexible end *l*, secured to the back of the pocket *a*, and which, as in the present instance, may be a continuation of the cord *f*. Fig. 4 shows the flap secured in position by the snap placed over the button. When the pockets are in their open or playing position, the free end of the cord *l* is carried over the face of the pocket *b* and the snap placed in position, as shown in Fig. 1, which effectively locks or holds the pockets in the positions shown.

As is usual in duplicate-whist-playing devices I may and preferably do employ means 30 for preserving the proper relation of the different hands in original and duplicate play. The arrow-heads shown associated with the pocket *a* or any other desired symbol may be used to mark a pocket or holder in each set, 35 which in the original play is to become the repository for the hand played by a selected one of the four players, which hand in the duplicate play is to be played by one of his opponents. Some other word, character, or 40 symbol, such as the word "dealer" shown in Fig. 1, applied to one of the pockets may be employed to determine the hand from which the leading card is to be played. This latter symbol will of course be applied to different 45 pockets relatively to the pocket designated by the arrow-head in the different sets of hands, in a set of sixteen original hands preferably appearing four times upon each pocket, so that each player will receive the lead four 50 times. These marks and indications are usual and well known in duplicate whist, and in whatsoever form or manner heretofore employed may also be used in connection with my invention. I preferably indicate the number 55 of the hand or set by a numeral placed upon the back of the pocket *a*, where it is the least exposed to observation and need not be seen during the duplicate play.

It will be obvious that the specific details 60 which I have herein described may be widely varied without departing from the spirit of my invention, and, further, that while I have here shown the same as embodied in a duplicate-whist device it may be employed with 65 suitable modification in many other games,

and may, moreover, be useful in other situations where separated cards or the like are to be held.

It often happens that where separate card-holding pockets are required in a device of this kind a receptacle is also desirable capable of holding the entire pack unseparated. This, for example, is desirable in duplicate whist, where it permits the utilization of the card-holder as a receptacle for the entire unseparated pack without the necessity for arranging the hands previous to the original play. In the form of my invention described reference to Fig. 6 will show how I am enabled to employ my card device as a pack-holder or card-case for holding the entire pack of cards unseparated when desired. The pack of cards may be inserted between any two of the pockets which separate to allow for its insertion, and when the flap is placed over the button *i* and the snap secures the same the cards are held on all four sides in a neat and convenient card-case. The cards may be kept in the case in this manner until the original hand is to be played, when they 90 may be dealt as usual, and after the original play inserted, each hand separately in its proper pocket, when the case is again closed up until needed in the duplicate play.

In Fig. 5 I have shown a modified form of means for fastening the flap and holding the pockets extended. This comprises as a substitute for the snap and button shown in Fig. 4 an ordinary form of paper-fastener, comprising the paper or other disk *m*, about 100 which may be twisted the free flexible end *l*, which in this instance is preferably a piece of fine twine.

Having thus described my invention, what I claim as new is as follows:

1. A collapsible card-holding device comprising a plurality of pivotally-connected card-holders holding their respective cards with their faces in substantially parallel relation in both the collapsed and extended positions of said device, thereby permitting said holder when extended to lie flat upon the table or other support.

2. A collapsible card-holding device provided with a plurality of holders having retaining-walls engaging the card-faces and having an opening and closing movement parallel with the retaining-walls.

3. A collapsible card-holding device comprising a plurality of card-holding pockets opened and closed by movements in substantially parallel planes and provided with means for securing said pockets in their extended positions.

4. In a collapsible card-holding device a plurality of pivotally-connected card-holders and means for defining the position of said holders when extended.

5. A collapsible card-holding device provided with a plurality of holders having an

opening and closing movement in the same general direction, and means for securing said holders in their extended and collapsed positions.

5. 6. A collapsible card-holding device having pivotally-connected card-holders for holding separated parts of a pack, and holding their respective cards with their faces in substantially parallel relation in both the collapsed and extended positions of said device, and means for holding the pack unseparated between said holders.

7. A collapsible card-holding device having

a plurality of card-holding pockets swingingly connected to collapse and extend by a ¹⁵ fan-like movement of one holder over another, separating means for determining the separation of said pockets when extended, and means for securing said holders when collapsed.

In testimony whereof I have signed my name ²⁰ to this specification in the presence of two subscribing witnesses.

ELROY N. HEATH.
